UNITED STATES PATENT OFFICE.

WALTER A. KEITH, OF LOS ANGELES, CALIFORNIA.

FLEXIBLE STAY-BOLT.

1,168,728.

Specification of Letters Patent. Patented Jan. 18, 1916.

Application filed October 28, 1914. Serial No. 869,010.

To all whom it may concern:

Be it known that I, WALTER A. KEITH, a citizen of the United States, residing at Los Angeles, in the county of Los Angeles and 5 State of California, have invented a new and useful Flexible Stay-Bolt, of which the following is a specification.

The primary object of this invention is to provide a novel connecting means between 10 the side and crown sheets of a fire box and the wrapper sheet thereof.

One of the most serious difficulties met with in fire box construction is occasioned by the great amount of expansion and contraction of the side and crown sheets, which 15 causes the stay bolts to snap and to become loose at their points of connection with the wrapper sheets. The plates composing the fire box wrapper sheet vary from one and 20 one-half times to double the thickness of the plates composing the crown and side sheets, and since the plates of the wrapper sheet are covered with lagging and a jacket, they are 25 protected from variation in outside temperatures. The other side of the wrapper sheet plates is covered with water and steam having 30 an average temperature, 387.7 degrees Fahrenheit. Hence, these plates have very little expansion and contraction comparatively speaking. The plates composing the 35 side and crown sheets vary in temperature from that of the atmosphere to 2800 degrees Fahrenheit, and therefore are subject to extreme contraction and expansion. Rigid 40 stay bolts securely fastening the side and crown sheets to the wrapper sheet become strained and distorted because of this constant expansion and contraction of the crown and side sheet, and also enlarge the openings 45 in the crown and side sheets causing leakage.

My invention aims to provide a means which will so connect several sheets of a boiler so as to overcome these difficulties, said means being strong, practical and cheaper of 50 maintenance.

With these and other objects in view, the invention consists of certain novel features of construction, combination and arrangement of parts, as will be hereinafter described, illustrated and claimed.

Referring to the drawings: Figure 1 is a rear elevation of a half of a fire box with the back plate removed. Fig. 2 is a section taken on the plane of line 2—2, of Fig. 1. Fig. 3 is 55 a fragmentary vertical sectional view through the boiler, showing my improved

connecting means. Fig. 4 is a section taken on the plane of line 4—4 of Fig. 1. Fig. 5 is a fragmentary vertical sectional view showing the relative position of the crown and side sheets of the fire box when expanded. Fig. 6 is a detail side elevation partly in section of one of the rivets. Fig. 7 is a perspective view of a somewhat spherical nut forming a part of the flexible stay bolts. 60 65

Referring in detail to the drawings by numerals, 1 designates the fire box wrapper sheet, 2 the fire box side and crown sheets, 3 a mud ring, and 4 the tube plate, all of which elements are of the usual construction found 70 in a locomotive boiler.

In carrying out my invention, I provide a plurality of girders or anchoring bands 5, which are placed between the wrapper sheet and the fire box crown and side sheets and 75 which may be of any length desired and arranged in any manner suitable for the purpose intended. These anchor bands are preferably made concavo-convex in cross section, as best shown in Fig. 4, and are secured to 80 the fire box crown and side sheets 2 in spaced relation thereto by any suitable fasteners such as the rivets 6 and 7. The rivets 6 have conical heads 8, extend through openings in the anchor bands, and have their inner extremities 9 of a reduced diameter to form a shoulder 10 engaging the outer walls of the fire box crown and side sheets 2. The reduced portions 9 extend through the sheets 85 of the crown and side sheets and are riveted 90 thereto. A collar or spacing washer 11 surrounds the shank of the rivets to maintain the anchoring bands at a fixed distance from the crown and side sheets.

The fasteners 7 are similar to the fasteners 6 with the exception that they have many sided heads 12 and a threaded reduced shank portion 13. Each of the fasteners 6 and 7 is provided with a tell-tale hole 6', as shown in Fig. 6. The specific 100 construction of these fasteners is unimportant so long as they serve to hold the bands rigidly to the crown and side sheets.

The bands are placed wherever it is desired to locate a series of stay bolts, and are formed with a plurality of rectangular slots 14 running longitudinally thereto. The stay bolts are designated as entireties by the numeral 15 and comprise T-bolts 16, sleeves 17, ball nuts 18, and caps 19. The heads 20 110 of the T-bolts will pass through the slots 14 when positioned in one direction, but will

not pass through the slots when turned transversely thereto. The other ends of the stay bolts are threaded and carry nuts 18 which are of semi-spherical construction 5 having faces which work within the semi-spherical sockets 21 of the sleeves 17. Each sleeve is externally threaded at one end to engage a threaded opening 22 formed in the fire box wrapper sheet, and similarly 10 threaded at its outer end to engage the interiorly threaded cap 19. Intermediate the two sets of threads a wrench flange 23 is formed.

In assembling a fire box of this construction, the anchor bands are first secured to the fire box crown and side sheets, then the T-bolts are passed through the registering openings in the fire box wrapper sheet and the anchor bands, and turned so that the 15 heads will extend transversely of the slots 14. Next, the sleeves 23 may be threaded into the openings 22 and finally the nuts 18 and caps 19 are positioned. As will be clearly apparent upon reference to Fig. 5, 20 my connecting means between the inner and outer sheets allows for the expansion and contraction of the sheets thereof without placing undue strain upon the stay bolts. In this figure, the side sheet of the 25 fire box is shown in its expanded position, at which time the openings 4 have been moved into their uppermost positions, raising the inner ends of the stay bolts slightly and causing the ball nuts 18 to turn in the 30 sockets 21 of the sleeve 17. The stay bolts may be easily removed by reversing the operations just described so as to permit the space between the sheets to be cleaned, and these bolts, as well as the anchor bands, 35 40 may also be used in other fire boxes and so have a long period of usefulness. The stay bolts now commonly employed can never be used except in connection with the fire box to which secured, and this makes it 45 necessary to discard the entire fire box as soon as the plates become weakened.

From the foregoing description taken in connection with the accompanying drawings, it will be seen that I have provided a very 50 practical fire box construction, making use of flexible stay bolts and of anchor plates

of such design that the stay bolts and anchor plates may be used again after the original fire box has become unfit for further use.

I do not wish to be limited to the exact 55 construction herein shown and described, but may make such changes as will fall within the scope and spirit of the appended claims.

What I claim is:

1. The combination with a fire box comprising side and crown sheets and a wrapper sheet, of an anchoring band secured to the outer surface of the fire box, crown and side sheets, and stay means pivotally secured to 65 the wrapper sheet and having a sliding connection to the anchoring band.

2. A fire box, comprising side and crown sheets and a wrapper sheet, a band rigidly secured to the crown and side sheet between 70 the two latter and the wrapper sheet, said band being provided with a plurality of elongated openings, and stay bolts connecting the wrapper sheet to the crown and side sheets, said stay bolts having shanks passing through the openings in the anchor band, being pivotally connected with the wrapper sheet, and having heads on their 75 inner ends of greater length than the width of said openings.

3. In combination with a pair of spacing plates, a strip secured to one of said plates, said strip being provided with an elongated opening, the other of said plates being provided with an opening alined with the first 85 mentioned opening, and a bolt passing through said openings, said bolt having a sliding connection with the strip and a universal connection with the second mentioned plate.

4. A stay bolt comprising a T-shaped bolt, a ball nut threaded onto one end of said bolt, a sleeve having a socket to accommodate said ball nut, and a cap threaded on the outer end of said sleeve.

In testimony whereof, I have hereunto set my hand at Los Angeles, Los Angeles, this 20th day of October, 1914.

WALTER A. KEITH.

In presence of—

LORRAIN E. DURROW,
RODNEY M. SMITH.
